VACUUM TANK

Filed Oct. 23, 1926

Patented May 3, 1927.

1,627,293

UNITED STATES PATENT OFFICE.

CHARLES S. NELSON, OF COCOYALIA, IDAHO.

VACUUM TANK.

Application filed October 23, 1926, Serial No. 143,626.

My present invention relates to improvements in vacuum tanks for use in liquid fuel feeding systems of internal combustion engines, adapted for use with automobiles, and for illuminating and heating burners and other similar appliances. The vacuum tank is of the type having a float control and maintained gasoline level, employing two floats in separated tanks. The floats by their movement automatically control suction from the vacuum tank, and feed of gasoline to the vacuum tank, as well as admission of gasoline from the vacuum tank to the feed tank, respectively, the feed tank being at all times in communication with the carbureter. The invention also embodies a valve device operated by one of the floats for controlling the suction line and air vent of the vacuum tank by means of which the parts are operated with efficiency and reliability. By the utilization of the device of my invention, a vacuum tank is provided which is simple in construction and operation, and in which the parts are compactly arranged to insure an efficient gasoline feeding system, by means of which a uniform and regulated feed of the gasoline to the carbureter is automatically accomplished.

The invention consists in certain novel combinations and arrangements of parts as will hereinafter be more fully pointed out and claimed.

In the accompanying drawings, I have illustrated one complete example of the physical embodiment of my invention wherein the parts are combined and arranged according to the best mode I have so far devised for the practical application of the principles of my invention.

Figure 1 is a vertical sectional view of a vacuum tank embodying my invention showing the air vent to the atmosphere open and the suction valve closed;

Fig. 2 is a transverse sectional view through the vacuum tank or chamber; and

Fig. 3 is an enlarged detail sectional view of the air valve device enclosed within the vacuum tank.

In carrying out my invention, I preferably use a pair of glass cylinders as 1 and 2, the former being used as the vacuum or inlet chamber, and the latter as the main feed tank. A flanged top 3 is provided for the vacuum tank and a similar flanged plate 4 is provided as the bottom of the main feed tank. Between the two glass cylinders is

interposed an intermediate partition 5 having double flanges, and gaskets or packing rings are used between the partition and the glass cylinders, as well as between the top and bottom members and the glass cylinders, to insure air and liquid tight joints. A suitable number of tie bolts 6 are used to connect the top and bottom members 3 and 4 together, and nuts are provided for clamping the cylinders and their end parts as indicated in Fig. 1.

The gasoline supply pipe 7 which is connected to a suitable supply tank is introduced to the upper portion of the vacuum tank through the top or lid 3, and a suction or vacuum pipe 8 is also connected to the top 3 and extends to the engine or motor. An air vent pipe 9 open to the atmosphere is also connected to the plate or disc 3 forming the top of the vacuum tank. The main feed tank 2 is provided with an outlet pipe 10 connected to the bottom plate 4, and a valve 11 in this pipe controls the flow of gasoline to the carbureter in usual manner. A drain cock 12 is also provided in the bottom plate 4 for draining the interior of the main feed tank 2.

An overflow vent port as 13 is provided in the intermediate partition 5, and a vent pipe 14 is connected thereto exterior of the tank and rises above the gasoline level in the vacuum tank 1, to perform the functions of an overflow pipe for the main feed tank.

For controlling the admission of the supply of gasoline through pipe 7, the suction pipe or line 8 is provided with a tubular casing 15 having a port 16, and the air vent pipe 9 is connected with a similar tubular casing 17 having a port 18. These two casings 15 and 17 are rigid with the top member 3 and project downwardly therefrom in the upper portion of the vacuum chamber. The tubular casings are spaced equidistant from the center of the cylindrical vacuum chamber and are closed except for their respective ports 16 and 18. These ports are controlled by slide valves 19 and 20, the former for the suction pipe and the latter for the air vent pipe. The valves as best seen in Fig. 3 are in the form of circular discs and they are held against the flat surfaces 18' which surround the ports in the two casings 15 and 17. The two valves or discs 19 and 20 frictionally engage these surfaces, and are adapted to slide vertically while in contact therewith. When the port

16 is closed, the port 18 is open, and vice versa.

The two valves are carried on a rock arm 21 located in the upper part of the vacuum chamber, and the valves are secured at the opposite ends of this arm by means of pins 22, in suitable manner. The rock arm is pivoted at 23 to a suspending bracket 24 that projects down from the under side of the tank top 3.

These two valves are controlled in their movements by a float 25 located in the vacuum tank. This float is fashioned with a central tube 26 to accommodate a stem 27, and the stem is provided with an upper stop member 28 and a lower stop member 29. The float is permitted to have a vertical movement with relation to the stem 27, before it strikes or contacts with either of these abutments or stop devices. The gasoline level in the vacuum tank is controlled by the float, and the valves when operated by the float are manipulated with a snap action to insure a quick and reliable opening or closing movement of the valves. For this purpose, a bell crank lever 30 is pivoted at 31 in a bracket 32 which also projects from the under side of the top 3 into the upper portion of the vacuum chamber, and the bell crank lever is pivoted at the lower end of this bracket. Two springs 33 are connected to the arm 34 of the bell crank lever, and anchored to the opposite sides of the bracket 32, and as seen in Fig. 1, the springs are offset from the pivot point 31 to insure a snap action when they become overbalanced. The bell crank lever is also pivoted at 35 to the vertically arranged stem 27 which passes through the float 25, and the bell crank lever 30 is provided with a pair of spaced arms 36. These arms are located in horizontal position and are adapted for coaction with the rock arm 21. One of the arms 36 projects across the rock arm and above it, while the other arm projects below the rock arm.

In Fig. 1, it will be apparent that when the level of the gasoline falls sufficiently to permit the float 25 to engage the stop 29, and then the level continues to fall carrying with it the float 25, the float will swing the bell crank lever until the springs 33 are overbalanced, and then with a snap action, the upper arm 36 will strike the rock arm 21 to cause opening of the suction valve port 16, and closing of the atmospheric valve port 18. Under these conditions, the gasoline is fed through the pipe 7 to the vacuum tank until the float 25 rises with the level of the

gasoline, and strikes the stop member 28. The continued rise of the float now operates the bell crank lever with a snap action, and the lower arm 36 strikes the rock arm 21 to cause the suction valve port to be closed and the atmospheric valve port to be opened, thus cutting off the supply of gasoline through pipe 7. These operations of the valves continue automatically while the feed system is in operation.

The gasoline passes from the vacuum chamber to the main feed tank 2 through a port 37 in the partition 5, and this port is controlled by a valve 38 pivotally carried at the end of a lever 39 which is pivoted at 40 on a bracket projecting from the under side of the partition 5. The valve 38 is controlled by a counterweight 41 on the lever 39 which counterbalances the float 42 pivotally supported from the valve and provided with a stem 43 which extends down into a guide tube 44 that is secured to the inner face of the bottom plate of the main feed tank. The rise and fall of the float 42 controls the admission of gasoline from the vacuum tank through port 37 to the main feed tank 2, and the gasoline is adapted to flow from the main feed tank at all times through the pipe 10 to the carburetor. The main feed tank is vented as described by the pipe 14.

It will be apparent from the above description taken in connection with my drawings that the floats in the vacuum chamber and main feed tank, by their movements, automatically control suction from the vacuum tank, and feed of gasoline to the vacuum tank and admission of gasoline from the vacuum tank to the feed tank, to insure a constant and uniform feed of gasoline to the engine or motor.

Having thus fully described my invention, what I claim as new and desire to secure by Letters Patent is:—

The combination with a vacuum tank having a tubular casing connected with the suction pipe and a second tubular casing connected with an air vent pipe, and ports in said casings, of a pivoted rock arm within the vacuum tank having a suction valve and an air vent valve at its opposite ends for co-action with said ports, a bell crank lever and an overbalancing spring therefor, a float operatively connected to said bell crank lever, and a pair of spaced arms on said lever for co-action with the rock arm.

In testimony whereof I affix my signature.

CHARLES S. NELSON.
